(57) **CLAIM**

The ornamental design for a floating thermometer, as shown and described.

DESCRIPTION

FIG. 1 is a perspective view of a new design for a floating thermometer according to one embodiment;

FIG. 2 is a front view of the floating thermometer illustrated in FIG. 1;

FIG. 3 is a top view of the floating thermometer illustrated in FIG. 1;

FIG. 4 is a left side view of the floating thermometer illustrated in FIG. 1;

FIG. 5 is a right side view of the floating thermometer illustrated in FIG. 1;

FIG. 6 is a perspective view of a new design for a floating thermometer according to another embodiment;

FIG. 7 is a front view of the floating thermometer illustrated in FIG. 6;

FIG. 8 is a top view of the floating thermometer illustrated in FIG. 6;

FIG. 9 is a left side view of the floating thermometer illustrated in FIG. 6;

FIG. 10 is a right side view of the floating thermometer illustrated in FIG. 6;

FIG. 11 is a perspective view of a new design for a floating thermometer according to yet another embodiment;

FIG. 12 is a front view of the floating thermometer illustrated in FIG. 11;

FIG. 13 is a top view of the floating thermometer illustrated in FIG. 11;

FIG. 14 is a left side view of the floating thermometer illustrated in FIG. 11; and,

FIG. 15 is a right side view of the floating thermometer illustrated in FIG. 11.

The portion of the articles depicted in broken lines is for illustrative purposes only and forms no part of the claimed design.
